United States Patent Office

Des. 216,580
Patented Feb. 17, 1970

216,580

JUG

David G. Hills, Collinsville, Conn., assignor to Monsanto Company, St. Louis, Mo., a corporation of Delaware

Filed Dec. 30, 1968, Ser. No. 15,136

Term of patent 14 years

Int. Cl. D9—01

U.S. Cl. D9—40

FIG. III

FIG. I

FIG. II

FIG. I is a front view of a jug, showing my new design;

FIG. II is a side view of the jug shown in FIG. I;

FIG. III is a partial sectional view taken through line 3—3 of FIG. I.

I claim:

The ornamental design for a jug, as shown.
